LAWN MOWING MACHINE

George A. Wegele, Otis, Kans. 67565

Filed Oct. 24, 1966, Ser. No. 4,396

Term of patent 14 years

(Cl. D40—1)

Fig.1.

Fig.2.

Fig.3.

Fig.4.

FIGURE 1 is a perspective view of the right side of the lawn mowing machine, showing my new design;

FIG. 2 is a front perspective view thereof;

FIG. 3 is a perspective view of the left side thereof; and

FIG. 4 is a rear perspective view of the lawn mowing machine.

The dominant features of the design reside in the portions shown in full lines.

I claim:

The ornamental design for a lawn mowing machine, as shown and described.
